(57) **CLAIM**

The ornamental design for a label printer, as shown and described.

DESCRIPTION

FIG. 1 is a front perspective view of the label printer, showing our new design;

FIG. 2 is a rear perspective view of FIG. 1.

FIG. 3 is a left side elevation view of FIG. 1.

FIG. 4 is a right side elevation view of FIG. 1.

FIG. 5 is a top plan view of FIG. 1.

FIG. 6 is a front side elevation view of FIG. 1.

FIG. 7 is a rear side elevation view of FIG. 1.

FIG. 8 is an illustrative reference view of FIG. 1 in a state of use; and,

FIG. 9 is an illustrative reference view of FIG. 1 in an alternative state of use.

The surfaces are lightly lined for contour only. The broken lines indicate disclaimed subject matter for environmental purposes only and form no part of the claimed design. No bottom view is provided as it is fully blocked by the disclaimed portions. The illustrative reference views in FIGS. 8 and 9 illustrate alternative states of use with adaptive portions in conjunction with the label printer, and form no part of the claimed design, and adaptive features are shown in broken lines further forming no part of the claimed design. The entire inner-inside surfaces as shown in FIG. 3 fully disclaimed and are bounded by and disclaimed by the broken lines, as shown. No claim is made to portions of the design which are not shown.
